UNITED STATES PATENT OFFICE.

MIKE VIDOS, OF RENTON, WASHINGTON.

SCYTHE.

Application filed December 1, 1924. Serial No. 753,265.

To all whom it may concern:

Be it known that I, MIKE VIDOS, a citizen of Yugoslavia, residing at Renton, in the county of King and State of Washington, have invented certain new and useful Improvements in Scythes, of which the following is a specification.

This invention relates to scythes and has for its object the provision of a novel construction whereby the reaper may assume an upright position while wielding the scythe and the scythe will be so disposed as to cut through the grain smoothly and close to the ground with a minimum effort upon the part of the reaper. The invention is illustrated in the accompanying drawing and will be hereinafter fully set forth.

In the drawing:

Figure 1 is a plan view of a scythe constructed in accordance with my invention, and

Fig. 2 is an edge view of the same.

In carrying out the invention, I employ a snath 1 which is preferably a straight bar having its lower end tapered slightly, as shown at 2. At the upper end of the snath is provided a grip 3 which extends from the snath at a right angle thereto and has near one end a recess or mortise to receive a reduced tongue 4 at the end of the snath, the tongue being held in the mortise by a dowel pin 5, as shown. A post 6 is secured to and extends from the snath at an intermediate point of the length thereof, and this post 6 is disposed at a right angle to the snath and also has its longitudinal axis at a right angle to the longitudinal axis of the grip member 3, as will be readily understood upon reference to Fig. 2. This post 6 is mortised into the snath and is held therein by a dowel pin 7. At the free end of the post 6 is a grip member 8 corresponding in form to the grip member 3 and extending from the post on a line parallel with the grip 3, as shown in Fig. 1.

The scythe blade 9 is provided at its butt end with a tang 10 seated against the under side of the snath 1 at the lower end thereof or in a shallow longitudinal recess provided in the snath and is held therein by a collar or gripping band 11 which encircles the lower tapered portion of the snath and the tang 10 of the scythe blade so that, if the collar be forced upwardly along the tapered

end portion of the snath, it will firmly grip 55 the tang and hold the same rigidly to the snath. The blade is connected with the lower or rear end of the tang 10 through an intermediate connecting web or tongue 12 and immediately adjacent and beyond the end 60 of the snath the tang and its connecting web or tongue is bent or twisted, as shown at 13 in Fig. 2, so that it and the width of the blade will be disposed in a plane parallel 65 with a plane passing through the centers of the grip members 3 and 8, which plane is indicated by the dotted line in Fig. 2.

From the foregoing description, taken in connection with the accompanying drawing, it will be seen that I have provided a very 70 simple and inexpensive scythe. As the post and grip members are connected to the snath by dowel pins and the blade is held to the snath by a collar or clamping band having a wedging engagement with the snath, it is 75 not necessary to employ any bolts in the production of my device the construction being simplified without any loss of strength and the cost of production being likewise 80 minimized. Inasmuch as the blade is disposed in a plane parallel with a plane passing through the grip members, the user may assume an erect position and the blade will be then held naturally so that it will cut 85 close to the ground and pass through the grain easily and smoothly.

Having thus described the invention, I claim:

In a scythe, a straight snath having a 90 tapered lower end, a grip member extending from the upper end of the snath at a right angle thereto, a post extending from an intermediate point of the snath at a right angle thereto and also at a right angle to the longitudinal axis of the grip member, a second grip member extending from the free 95 end of the post parallel with the first-mentioned grip member, a blade, a tang rigidly connected with the butt end of the blade in fixed angular relation thereto, the width of the blade being disposed in a plane parallel with a plane passing through the centers of the grip members, and a clamping collar encircling the tang and the lower tapered end 100 of the snath and having a wedging binding engagement with the snath.

In testimony whereof I affix my signature.

MIKE VIDOS. [L.S.]
